No. 37,220.

Patented November 15, 1904.

UNITED STATES PATENT OFFICE.

GEORGE H. BARRETT, JR., OF NEW YORK, N. Y., ASSIGNOR TO WILLIAM R. PHELPS & CO., OF NEW YORK, N. Y., A FIRM.

DESIGN FOR A SPOON.

SPECIFICATION forming part of Design No. 37,220, dated November 15, 1904.

Application filed October 22, 1904. Serial No. 229,615. Term of patent 3½ years.

To all whom it may concern:

Be it known that I, GEORGE H. BARRETT, Jr., a citizen of the United States, and a resident of New York, borough of Manhattan, in the county of New York and State of New York, have invented a certain new, original, and ornamental Design for a Spoon, of which the following is a specification.

In the accompanying drawings, Figure 1 is a view of the obverse side of a spoon having 10 my design applied thereto, and Fig. 2 a view of the reverse side of the same.

What I claim is—

The ornamental design for a spoon, as shown.

GEORGE H. BARRETT, JR.
